(57) **CLAIM**

I claim the ornamental design for a chronograph timepiece, as shown and described.

DESCRIPTIONFIG. 1 is a front elevational view of a chronograph timepiece showing my new design; and,
FIG. 2 is a right side elevational view thereof, the left side being a mirror image thereof.

The rear is plain, unornamented and not being claimed as a part of my design.

1 Claim, 2 Drawing SheetsFIG. 1

FIG. 2
